UNITED STATES PATENT OFFICE.

PATRICK J. LYONS, OF PHILADELPHIA, PENNSYLVANIA.

RAILWAY-CROSSING FROG.

1,322,707.

Specification of Letters Patent. Patented Nov. 25, 1919.

Application filed August 22, 1919. Serial No. 319,047.

To all whom it may concern:

Be it known that I, PATRICK J. LYONS, a citizen of the United States, residing at Philadelphia, county of Philadelphia, and

5 State of Pennsylvania, have invented a new and useful Improvement in Railway-Crossing Frogs, of which the following is a full, clear, and exact description, reference being had to the accompanying drawings, which 10 form a part of this specification.

My invention relates to a railway track construction for use in crossing and frogs, on either steam or street railway lines, of such a character as to permit of the ready 15 removal and replacement of the parts receiving the greatest wear without interfering with or damaging other parts.

In a crossing, for example, the point where the wheel flangeways meet is subject to 20 greater wear than any other part of the track, due to the jumping of the wheel over the intersecting flangeway. It is customary to place a removable plate or center in the track at this point, in order to permit of 25 renewal of the worn portion without the necessity of renewing the entire crossing. The devices for this purpose are found to have many defects. Thus, they are difficult to remove and their removal frequently re- 30 sults in irreparable damage to the entire crossing. Again, a crossing, frog, or the like is subjected, whenever a wheel strikes the intersecting point, not only to one blow or shock, but to one and frequently two im- 35 mediately following secondary blows or shocks, the effect of which frequently is to break the rail adjacent to the center.

The object of my invention is to much prolong the life of the crossing, frog or the 40 like. Another object of the invention is to provide an insert or center which will be held rigidly in position, but which, if worn, may be readily removed and replaced, thus imparting to the crossing a length of life 45 equal to that of the rails themselves.

The invention comprises a crossing, frog, or other track construction comprising a pocketed support for a center, a removable center, preferably of manganese or other 50 especially hard or hardened steel, engaging the pocketed support, and rail sections, separated from or integral with the support, partly embraced by said support and abutting against both the support and the center, the construction being such that the center can be held in and on the support 55

by means of bolts or poured-in metal, or both, so as to permit ready removability and replacement.

A preferred embodiment of the invention 60 is shown in the drawings, wherein—

Figure 1 is a plan view of the invention as applied to a crossing only one of the four intersections being shown.

Fig. 2 is a side elevation of the same, showing one rail end in section.

Fig. 3 is a section on the line 3—3, of Fig. 2.

Fig. 4 is a section on the line 4—4, of Fig. 1.

Fig. 5 is a plan of one of the center supports.

Fig. 6 is a perspective view of the corresponding center.

Fig. 7 is a perspective view of the center 75 slightly modified.

Fig. 8 is a perspective view of an entire intersection with two of the rail sections omitted and one of the arms of the center support shortened.

The crossing intersection shown in all the figures comprises rail sections *a*, *a*, etc., a center plate and a center plate support.

The support is composed of diverging pocketed members, each comprising a base *b* 85 and sides *c*, *d*. As shown in Fig. 8, the sides *c* and *d* may be made separate, sides *c* being integral with the base *b*, while sides *d* are fish plates riveted to the base by means of rivets *e* entering rivet holes *e'*. The bottom of 90 the pocket formed by the base *b* and sides *c*, *d* is above the level of the base of the corresponding rail sections.

Sides *c*, *d* may be made integral, the whole center plate support *b*, *c*, *d*, being cast to 95 shape in one piece, as shown in Fig. 5; or it may be cast roughly to shape and then machine grooved to form the pocket and drilled to form the rivet holes; or the center plate support and abutting rails may be 100 cast in one piece, the pockets being cast with the structure or subsequently machine-grooved. In this construction, of course, there would be no rivet holes. Again, if the rail sections are not cast with the center 105 plate support, they may be cast-welded, instead of riveted, thereto.

The removable center plate, which is preferably of manganese steel, comprises diverging arms each composed of a head *f* and a 110 web *g*. The web *g* is of less height than the webs of the rail sections *a* (say of about half

the height) but is of sufficient height to fill the pocket of the corresponding supporting member. The heads of the center plate rest upon the upper edges of the sides *c*, *d*, of the 5 supporting members.

The sides of the supporting members extend beyond the base thereof and embrace the webs of the rail sections and are riveted thereto by means of rivets *h* extending 10 through rivet holes *h'*.

It will thus be seen that the rail sections *a* and the center plate support *b*, *c*, *d*, are permanently secured together, leaving a central pocketed portion to receive and support 15 the center plate *f*, *g*, the heads and webs of which abut against the heads and the upper halves of the webs of the rail sections.

There being no effective force tending to dislodge the center plate from its support 20 or out of alignment with the rail sections, I prefer to bolt the center plate in place by means of bolts *i* passed through bolt holes *i'* near the ends of the webs of the center plate.

25 After the center plate is positioned and the bolts entered through the sides of the support and the webs of the center plate, molten metal, either zinc or lead, may be poured in to fill any irregular spaces that 30 may exist in the pocket or recess of the center plate support, thereby insuring the rigidity and solidity of the structure. The center may be easily and quickly removed by releasing the bolts and using two pinch 35 bars to pry up the center plate. The bolts may not be necessary, as it is probable that the poured-in zinc, Babbitt metal or the like will itself firmly hold the center plate in position, as the metal will flow into the bolt 40 holes and adhere to the sides of the casting.

The center plate formed and inserted as described is adapted to sustain such shocks, whether two or three in number, as are sustained by the crossing when a wheel passes 45 the intersecting grooves and save the abutting rail sections from the effects of the secondary shock or shocks and thus impart to the crossing a life equal to that of the rails themselves.

50 In Figs. 7 and 8, the webs of the center plate are reinforced at *m*, the sides of the pocket at the point of intersection being shaped to receive the reinforced portion *m*.

Having now fully described my invention, what I claim and desire to protect by 55 Letters Patent is—

1. A track construction comprising a center-support having diverging pocketed arms, said arms being integrally united at 60 their junction, an integral center having diverging heads overlying the support and

webs engaging the pockets of said arms, and rail sections abutting against both the respective arms of the support and the respective members of the center, the floors of the 65 pockets and the bottom edges of the webs of the center being above the feet and below the heads of said rail sections, said center being removably secured in said pocketed arms. 70

2. A track construction comprising a pocketed support for a center, an integral removable webbed center engaging the pocketed support, and rail sections abutting against both the support and the center, the 75 webs of the rail sections being embraced by extended sides of the support, the floor of the pocket and the bottom edges of the webs of the center being between the levels of the heads and feet of said rail sections, the extended side of the support overlying the bases and underlying the heads of the respective rail sections. 80

3. A track construction comprising rail sections, a center plate support having 85 diverging members abutting against the respective rail sections, said diverging members being integrally united at their junction, each diverging member shaped to form an elongated pocket whose sides project 90 beyond the abutting end of the corresponding rail section and inclose the web and extend over the base and under the head of such rail section, and a removable center plate having integrally united diverging 95 arms each composed of a head and web engaging and supported by a corresponding pocketed member of the support. 100

4. A track construction comprising rail sections; a center plate support having diverging members abutting against the respective rail sections, each diverging member shaped to form an elongated pocket whose floor is above the level of the foot of the corresponding rail section and whose sides project beyond such rail section and inclose the web and extend over the base and under the head of such rail section; a removable center plate having diverging 105 arms each composed of a head and web engaging and supported by a corresponding pocketed member of the support, the webs of the center plate being of less height than the webs of the rail sections, which latter thus abut partly against the center plate and partly against the center plate support; and means to removably secure the center plate in its pocketed support. 110

In testimony of which invention, I have hereunto set my hand, at Philadelphia, on 115 this 14th day of August, 1919.

PATRICK J. LYONS.
